UNITED STATES PATENT OFFICE.

DAVID MCERLANE, OF GLASGOW, SCOTLAND.

PUMP FOR INFLATING PNEUMATIC TIRES AND THE LIKE.

Application filed August 29, 1922. Serial No. 585,007.

To all whom it may concern:

Be it known that I, DAVID MCERLANE, a subject of the King of Great Britain and Ireland and the Isle of Man, and a resident 5 of 51 Bedlay Street, Springburn, Glasgow, Scotland, have invented new and useful Improvements in and Relating to Pumps for Inflating Pneumatic Tires and the like, of which the following is a specification.

10 This invention has reference to improvements in and relating to pumps for inflating pneumatic tires and the like and particularly relates to that type of pump in which a piston is reciprocated within a 15 cylinder by means of levers, rods and links actuated by the foot of the operator.

According to this invention the pump consists of two pistons which operate in the same cylinder and are actuated simultaneously by suitable mechanism operated 20 by the foot of the operator.

The construction and arrangement of the parts of the pump is such that when it is not in use it may be collapsed so as to occupy as little space as possible.

25 In order that others skilled in the art to which this invention relates may properly understand the same I have hereunto appended two sheets of explanatory drawings 30 in which:—

Figures 1 and 2 are respectively an elevation and a plan view of a pump as constructed according to this invention while Figures 3 and 4 are end views.

35 In Figures 1 and 3 the lever mechanism when in the extended position is indicated by dotted lines.

Figure 5 is a longitudinal sectional elevation of the cylinder and the pistons of said 40 pump.

Referring to these drawings,

In carrying the improvements of this invention into effect or practice an open ended cylinder 1 is formed or provided with a bracket 2 at each end. Two pistons 21—21 located in the cylinder 1 have their piston rods 22—22 which protrude from the ends of the cylinder 1, fitted with cross-heads 3 and 4.

50 Two rods 5 are secured to the crosshead 3 at the end of the one piston rod 21; one on each side of the cylinder 1.

These rods 5 slide through holes in the bracket 2 at the end of the cylinder. Another pair of rods 6 are similarly secured

to the crosshead 4 at the end of the other piston rod 21 and these rods 6 slide through holes in the bracket 2 at the other end of the cylinder. A guide rod 7 preferably of polygonal shape in cross section is secured on each side of the cylinder 1 between the brackets 2. A pair of slidable crossheads 8 and 9 are adapted to slide on each rod 7. The crossheads 8 are secured to the rods 6 while the crossheads 9 are secured to the rods 5. The rods 5 and 6 are so arranged that the one clears the other.

The polygonal shape of the rods 7 prevents the crossheads 8 and 9 from turning or partially rotating round the rods.

70 The foot operated lever 10 consists of a double lever, the limbs of which are mounted on a hinge pin or cross rod 11 carried by lugs 12 fitted to or formed in one with one of the brackets 2.

75 At a suitable position on this foot lever 10 the upper ends of two pairs of links 13 and 14 are pivoted. The lower ends of the links 13 are pivoted to the crossheads 8 while the lower ends of the links 14 are pivoted to the crossheads 9.

80 The lever 10 would be provided with a suitably constructed tread bar or surface 15. The cylinder 1 would be provided with the usual pressure gauge and tire connection connected to the outlet branch 16. The pistons 21—21 are of that type which consist of two collars 23 mounted on the piston rods 22 and having between said collars leather washers 24 of cup form. When 85 the pistons 21—21 are on the in stroke compressing the air between them the pressure of the air expands the edges of the cup leathers 24 so that the air cannot pass the pistons but is forced through the central 90 discharge outlet 16 which is preferably provided with a spring controlled non-return ball valve of well known construction (not shown). When the pistons 21—21 are on the out stroke, the suction action in the 100 cylinder 1 between the pistons 21—21 draws the air by the pistons from the open ends of the cylinder 1.

95 A spring 17 is mounted on the cross rod 11 so as to return the levers and pistons 105 21—21 after the foot lever 10 has been depressed to deliver the air.

100 A catch lever 18 mounted on a bracket 19 fitted to one of the end brackets 2 is adapted to engage the foot lever 10 so as to hold 110

same downwards when the pump is not in use.

Stops 20 are fitted on the rods 7 to limit the travel of the crossheads 8 and 9.

5 I claim.

1. In a pump for inflating pneumatic tires and the like, a cylinder; piston rods protruding from both ends of said cylinder and provided with crossheads; rods connecting said crossheads with other crossheads adapted to slide on guide rods; and an arrangement of a lever and links for actuating the same, substantially as herein set forth.

15 2. In a pump for inflating pneumatic tires and the like, a cylinder; a foot operated lever connected by means of links to slidable crossheads and adapted to reciprocate towards and from each other a pair of 20 pistons arranged in said cylinder substantially as herein set forth.

25 3. A pump comprising an open ended cylinder barrel; a pair of pistons mounted therein; a piston rod fitted to each piston and protruding one from each end of said barrel; a crosshead at the extremity of each protruding piston rod; members adapted to reciprocate in a direction parallel with the axis of said barrel and located on each 30 side of said barrel; guiding means for said members; means for reciprocating said members; and means connecting said members with said crossheads so that the recip-

roating movement of said members is imparted to said crossheads.

4. A pump comprising an open ended cylinder barrel; two pistons adapted to reciprocate to and from each other in said cylinder barrel; a piston rod fitted to each piston and protruding one from each end of said barrel; a crosshead at the extremity of each protruding piston rod; guide rods located one on each side of said barrel; crossheads slidably mounted on each guide rod; and connecting rods for associating respectively said first-mentioned and second-mentioned crossheads; and means for reciprocating said crossheads.

40 5. A pump for inflating pneumatic tires and the like comprising a pump frame; an open ended cylinder barrel supported thereby; a pair of pistons adapted to reciprocate to and from each other in said barrel; a piston rod fitted to each piston and protruding one from each end of said barrel; a crosshead at the extremities of each protruding piston rod; guide rods located one on each side of said barrel; crossheads 45 slidably mounted on each guide rod; connecting rods extending between the first-mentioned and second-mentioned crossheads; a foot operated treadle lever pivoted on said pump frame; and a pair of links connecting said treadle lever with the 50 said slidable crossheads.

55 DAVID McERLANE.
